UNITED STATES PATENT OFFICE.

WILLIAM L. LENGEL, OF READING, PENNSYLVANIA, ASSIGNOR TO THE NOLDE & HORST CO., OF READING, PENNSYLVANIA, A CORPORATION OF PENNSYLVANIA.

YARN-CHANGE ATTACHMENT FOR CIRCULAR-KNITTING MACHINES.

Application filed November 12, 1921. Serial No. 514,509.

My invention relates to circular knitting machines having a yarn change mechanism, and my object is to provide yarn-clamping means that will firmly grip and hold, without interference, the several yarn ends when intermittently cut off and withdrawn from the knitting action, and which will positively deliver to the needles for resumption of knitting any of said held yarn ends without 5 freeing unintentionally any other held end; my improvements including a special yarn-end holder device for each of the usual yarn-guides, cooperatively actuated with the latter, and adapted to grasp a withdrawn yarn 10 end, and to move with the corresponding guide to positively deliver its yarn to the needles for resumption of knitting. The invention is fully described in connection with the accompanying drawings and the novel 15 features are pointed out in the subjoined 20 claims.

Fig. 1 is a plan view of a portion of a knitting machine having my invention applied thereto.

Fig. 2 shows an elevation of material in Fig. 1.

Fig. 3 is a partial inner view of the developed latch ring showing the cooperative relation of my yarn-end holder with the 30 yarn guide and cutter device, and Fig. 4 is a detail section on the line 4—4 of Fig. 3.

Figs. 5, 6 and 7 are diagrammatic views showing different operative positions of the yarn-guide and my cooperatively actuated 35 yarn-end holder device.

The drawings indicate a common type of knitting machine and only such parts are shown as are necessary to fully explain my invention. The yarn change mechanism is 40 old and employs as usual a number of yarn guides 5, 5, 5, 5 for the several yarns, which are pivotally mounted with their eyeleted ends 6, 6, 6, 6 adapted to be swung by their respective springs 7 into the throat 8 of the 45 latch ring 9, in yarn feeding position adjacent the needles 10; or the guides may be swung into non yarn feeding position by their respective levers 11 each operated in the usual manner from the pattern mechanism 50 by a rod or wire 12, all of which is well known and requires no further explanation of its operation. The only departure shown in the drawings from the standard parts heretofore employed in the above de-

scribed well known mechanism are, the slight 55 modification in the shape of the yarn guides and the re-location of their fixed pivotal support 15 so as to cause said guides to swing in an arc substantially tangential to the circular series of needles instead of 60 through the latter as heretofore; and the addition of a pivoted arm 16 on each of the usual levers 11. The springs 17 on the rods 12 are merely supplemental to springs 7, and are not essential. 65

The necessity of holding the cut ends of the several yarns until their reengagement in the knit fabric has heretofore been recognized, but the means commonly employed have not been satisfactory or positive, interference of the yarns and the unintentional pulling free of an additional yarn with the one intended causing imperfect and defective knitting; besides the common location of the holding means in the space within the 75 circular series of the needles interferes with or prevents the addition of other attachments to the machine limiting its usefulness. My invention relates to improved 80 holder devices adapted to positively grasp and retain each yarn free of the others and positively deliver the same to the needles, and my devices are located normally entirely outside the circle of needles. As stated heretofore I employ a yarn-end holder 85 device for each yarn guide, all identical in construction and operation, so that in the following description it will be necessary only to describe one holder device and its 90 operation in order to make clear my invention.

Referring now particularly to Figs. 5, 6, and 7 in which my yarn-end holder device is shown in detail on a large scale, 20 represents a spring-retracted swinging arm pivotally supported at one end on a fixed shaft 21, and carrying at its free end a yarn-gripping member 23 intermediately pivoted thereto at 24, the forward end of said member having a downwardly bent portion 25 forming one part of a yarn clamping jaw, and the cooperating jaw-part 26 being part of a member-carried slide-bar 27 normally moved to jaw-closing position by a spring 28. The end 29 of member 23 opposite the jaw-clamping end is enlarged as shown and provided with a slot 30 engaging a fixed shaft 31, such engagement combined with

the pivotal movement of arm 20 determining the arc of swing of the clamping jaws 25-26.

The opening movement of said jaws 25-26, acting against the closing action of spring 28, is provided for, as shown, by a plate 35 pivotally carried from the free end of an actuating arm 36 mounted on pivot shaft 37, said plate having a slotted aperture 38 engaging a stud 39 on slide bar 27, and a spring 40 acting on said plate is adapted to engage the recessed portion 38^a of said slot 38 with the stud 39, as clearly seen in Fig. 6, upon the forward movement of the jaw-carrying member 23 and its swinging arm 20, the latter also actuating arm 36 through stud 41 and slotted aperture 42 therefor in the respective arms, to cooperatively move plate 35. The reverse movement of arm 20, retracting member 23, also causes plate 35 through its actuating arm 36, to retract slide bar 27 due to said engagement of the stud 39 and slot recess 38^a, as clearly seen in Fig. 7. The freeing movement of said stud engagement in recess 38^a is provided for as shown in dotted lines Fig. 7, by a projection 5^a on yarn guide 5 adapted to contact with and lift the free end of arm 35, the stud 39 then having limited movement in the slot 38 permitting the slide bar 27 to close the jaws 25-26 upon the yarn which has been carried between them upon the upward swing of the guide, the parts assuming the starting position of Fig. 6. Swinging movement is imparted to arm 20 by arm 16 pivotally carried by lever 11 and normally bearing against said arm 20 to move the latter when lever 11 is rocked to free guide 5 to the lowering action of its spring 7, spring 17 aiding this movement; and the arm 16 is pivotally swung, as by a pattern controlled bar 49, to free the swinging arm 20 to the retractive movement of its spring 20^a.

45 The cutting device, as clearly seen in Figs. 1 and 3, is formed in a bracket 50 carried on the latch ring 9 and having a plate 51 depending into said ring substantially coincident, as indicated, with the usual knitting wave of the needles 10, said plate having an aperture provided with a fixed cutter blade 52 and a movable blade 53, the latter being provided with an actuating arm 54 intermittently operated by a pattern controlled lever 55. When it is desired to withdraw a yarn from the knitting action, its guide 5 is elevated as usual, such movement carrying its yarn under the plate 51 between the cutter blades 52, 53 which operate to sever the 50 yarn, such upward movement of the guide 5 as previously stated, carrying the yarn into the open jaws 25-26 of my holder device which close upon the same and firmly grasp the cut end as previously described.

60 The operation of my device is as follows:

Assuming that the yarn guide 5 is in raised non yarn feeding position, my cooperatively actuated holder device will assume the position indicated in Fig. 5 with the jaws 25-26 firmly grasping the cut off end of the yarn extending beyond the eyelet 6 of said guide. When it is desired to resume knitting with this withdrawn yarn, the rod 12 is actuated in the usual manner by the pattern mechanism to rock lever 11 and permit spring 7 to lower guide 5 to yarn feeding position in the throat 8 of the latch ring 9 as common in yarn change knitting machines, such rocking movement of lever 11, through its pivoted arm 16, swinging arm 20 and its pivotally carried member 23 to position the jaws 25-26 just inside the circular series of needles, as clearly seen in Fig. 6, the yarn end extending from said jaws through the needles to the guide eye 6, and the jaws maintaining their grip upon the yarn until the needles positively engage and forcibly withdraw it, absolutely insuring its proper reentry into the knitted fabric. After the yarn has been forcibly withdrawn from the jaws 25-26 the latter are retracted by action of pattern controlled bar 49 tilting arm 16 and freeing swinging arm 20 to the retractive movement of its spring 20^a, such movement, as stated opening the jaws through the engagement of stud 39 in slot recess 38^a, the device assuming the position indicated in Fig. 7, and the yarn guide 5 remaining in lowered feeding position as shown. When the pattern mechanism operates to withdraw the yarn by lifting guide 5 as usual, the projection 5^a on the latter as heretofore described, frees stud 39 from engagement in recess 38^a permitting the closing of the jaws 25-26 upon the yarn carried between them by the rising guide, and the cutter device is operated to sever the yarn extending from the last needle engaged thereby to the raised guide, the yarn in such position lying between the cutter blades 52-53 as heretofore described.

It will of course be understood, as heretofore stated that in connection with each yarn guide 5 there is provided a yarn-end holder device of my novel construction and operation as above fully described; that the shafts 15, 21, 31, and 37, acting as pivotal supports, may desirably be mounted in the usual latch ring extension 9^a and serve alike for all the guides and holders employed; and that one pattern controlled bar 49 will suffice as it acts only upon the arm 16 when in tilted position as indicated in Fig. 6. It will also be readily understood that the preferred embodiment of my invention above fully described may be quickly and cheaply applied to any well known type of knitting machine having the usual yarn change mechanism, the application requiring no change in the usual knitting or yarn changing mech-

anism with which it cooperates. The normal location of my holding devices being entirely outside the circular series of needles it leaves free the space within the same for 5 other desirable attachments heretofore impossible in machines having a yarn change mechanism, and the individual gripping of each yarn prevents any possible interference of the several yarns employed, while 10 the carrying of the yarn end to the needles to reenter the same into the knitting action and the maintaining grip thereon until forcibly withdrawn by the needle engagement absolutely prevents any failure of the yarn 15 reentry when desired. Modifications within the spirit of my invention will readily suggest themselves and I do not desire to limit myself to the specific construction shown and described.

20 What I claim is:—

1. In a circular knitting machine comprising a rotary needle cylinder, a yarn-cutter device, a yarn-guide movable into and out of feeding relation to said needles, and a pattern-controlled actuating lever for said guide, a separately movable cooperative yarn-end holder for said guide, a lever-carried arm engageable with said holder to simultaneously move said guide and holder 25 in a yarn-feeding direction, and means to disengage said arm and free said holder for independent reverse yarn-receiving movement.

2. In a circular knitting machine comprising a rotary needle cylinder, a yarn-cutter device, a yarn-guide movable into and out of feeding relation to said needles, and a pattern-controlled actuating lever for said guide; a separately movable cooperative 30 yarn-end holder for said guide having clamping jaws, jaw opening and closing mechanism, a lever-carried arm engageable with said holder to simultaneously move said guide and holder in a yarn-feeding direction, means to disengage said arm and free said holder for independent reverse 35 yarn-receiving movement and simultaneous operation of said jaw opening mechanism, and guide carried means effective during 40 movement to non-feeding position to actuate said jaw closing mechanism.

45 3. In a circular knitting machine comprising a rotary needle cylinder, a yarn-cutter device, a yarn-guide movable into and out of feeding relation to said needles, and a pattern-controlled actuating lever for said 50 guide; a swinging arm above said guide pivotally carrying a yarn-end holder having normally closed clamping jaws, a lever-carried arm engageable with said swinging arm to simultaneously move the latter and its pivotally carried closed jaws with said guide in one movement of the latter, means to dis-

engage said lever-carried arm and free said swinging arm for independent reverse movement with its pivoted jaws, jaw-opening means actuated by said reverse movement, and jaw-closing means actuated by subsequent independent movement of said guide. 65

4. In a circular knitting machine comprising a rotary needle cylinder, a yarn-cutter device, a yarn-guide movable into and out of feeding relation to said needles, and a pattern-controlled actuating lever for said guide, a swinging arm above said guide pivotally carrying a yarn-end holder having normally closed clamping jaws provided with a swing controlling slot, a fixed guide engaging in said slot, a lever-carried arm engageable with said swinging arm to simultaneously move the latter and its pivotally carried closed jaws with said guide in one movement of the latter, means to disengage said lever-carried arm and free said swinging arm for independent reverse movement 70 with its pivoted jaws, jaw-opening means actuated by said reverse movement, and jaw-closing means actuated by subsequent independent movement of said guide. 75

5. In a circular knitting machine comprising a rotary needle cylinder, a yarn-cutter device, a yarn-guide movable into and out of feeding relation to said needles, and a pattern-controlled actuating lever for said guide; a swinging arm above said guide pivotally carrying a yarn-end holder having normally closed clamping jaws, jaw opening and closing mechanism, a lever-carried arm engageable with said swinging arm to simultaneously move the latter and its pivotally carried closed jaws with said guide in one movement of the latter, means to disengage said lever-carried arm and free said swinging arm for independent reverse movement with its pivoted jaws, a jaw-opening 80 lever actuated by said reverse arm movement, and a guide carried trip adapted to effect a jaw closing movement. 85

6. In a circular knitting machine comprising a rotary needle cylinder, a yarn-cutting device, a plurality of yarn guides separately movable into and out of feeding relation to said needles, and a corresponding series of pattern-controlled actuating levers for said guides; a yarn-end holder mechanism for 100 each of said guides movable with its respective guide into yarn delivering position, and independently reversely movable into yarn-receiving position, a series of lever-carried arms each engageable with its respective 105 holder to cooperatively move the same with its guide, and a pattern-actuated member adapted to disengage any such engaged arm. 110

In testimony whereof I affix my signature.

WILLIAM L. LENGEL.
